UNITED STATES PATENT OFFICE.

JONATHAN JOHNSTON, OF MORGAN PARK, ILLINOIS, ASSIGNOR TO
HERBERT O. BENNETT, OF CHICAGO, ILLINOIS.

DESIGN FOR AN OIL-BURNER RETORT.

SPECIFICATION forming part of Design No. 27,176, dated June 8, 1897.

Application filed April 19, 1897. Serial No. 632,874. Term of patent 7 years.

To all whom it may concern:

Be it known that I, JONATHAN JOHNSTON, a citizen of the United States, residing at Morgan Park, in the county of Cook and State of Illinois, have invented and produced a new and original Design or Useful Shape for an Oil-Burner Retort, of which the following, taken in connection with the accompanying drawings, is a full, clear, and exact specification.

In the said drawings, Figure 1 is a bottom plan of an oil-burner retort embodying my design, and Fig. 2 is a transverse sectional view thereof.

The leading features of my design consist of the annular welt or ring-like formation A, surrounding a smaller ring or annular flange B, and the web C, filling the space between the sides of the ring A and forming a backing for the ring B.

The annular welt or ring A forms the margin or outline of the retort. It is cylindrical in cross-section, as shown in Fig. 2, and its inner edge is gradually rounded off into the flat web C, which lies to one side of the center

of the welt A, so that on one side of the retort there will be a flat surface, as shown in Fig. 2, formed by one face of the web C, the welt A and the ring B projecting wholly from the other face of such web. The ring or annular flange B projects substantially at right angles from the plane of the web C and extends nearly to the plane in which the outer edge of the welt A lies. The web C extends entirely across the ring B from side to side of the annular welt A.

From one side of the annular welt A project three protuberances D E F, which lie in the plane of the annular welt A.

Having thus described my invention, what I claim as new therein, and desire to secure by Letters Patent, is—

The new and original design or useful shape for retorts for oil-burners substantially as herein shown and described.

JONATHAN JOHNSTON.
